UNDERGARMENT

Filed June 11, 1927

FIG. 1.

FIG. 3.

F. E. McGill,
INVENTOR

BY *Victor J. Evans*

WITNESS:

ATTORNEY

UNITED STATES PATENT OFFICE

FRANK E. MCGILL, OF SACRAMENTO, CALIFORNIA

UNDERGARMENT

Application filed June 11, 1927. Serial No. 198,162.

This invention relates to improvements in garments and has especial reference to undergarments, an object being to provide means located at the waist of the garment for 5 relieving strain and preventing tearing due to stooping or other body movements of the wearer.

Another object of the invention is the provision of means of the above character which 10 are simple and economical in construction and which will not render the appearance of the garment bulky.

With the above and other objects in view, the invention further includes the following 15 novel features and details of construction, to be hereinafter more fully described, illustrated in the accompanying drawings and pointed out in the appended claim.

In the drawings:—

20 Figure 1 is a rear elevation showing an undergarment constructed in accordance with the invention.

Figure 2 is an enlarged section on the line 2—2 of Figure 1.

25 Figure 3 is a similar view showing the plaits extended.

Referring to the drawings in detail wherein like characters of reference denote corresponding parts, the invention is shown in 30 connection with an undergarment of a particular type, but it is capable of use in connection with other types of garments. The garment shown includes an upper member 10 and a lower member 11 which are connected at the waistline, the connection at the back 35 of the garment being affected by means of the present invention. It may be here stated that the invention may either be applied to the back of the garment or may extend entirely 40 around the waist.

The invention comprises a strip which is formed of a plurality of sections 12. These sections are longitudinally plaited as shown at 13, so that the plaits extend horizontally 45 along the waist. The plaited sections 12 are connected by elastic sections 14, the edges of these elastic sections being secured to the adjacent ends of plaited sections 12. The elastic sections are also secured to the pleated sections between the plaits by any suitable

means, such as by stitching, indicated at 14'. This stitching is shown in Figures 2 and 3 of the drawings and as shown in these figures acts to hold the plaits properly spaced when the strip is either contracted or expanded. A binding 15 extends along the upper and lower edges of the strip and this binding is connected to the upper and lower members of the garment through stitching or other suitable means.

It will be apparent that when the wearer of the garment bends forward, the plaits which normally occupy the position shown in Figure 2 will be extended to substantially the position shown in Figure 3 and when the wearer again assumes an upright position, the plaits will be returned to their normal or folded position through the action of the elastic sections 14.

The invention is susceptible of various 70 changes in its form, proportions and minor details of construction and the right is here reserved to make such changes as properly fall within the scope of the appended claim.

Having described the invention what is 75 claimed is:—

A garment comprising a body portion and legs, a pleated strip secured horizontally at the waistline of the garment and connecting the body and legs, and spaced elastic strips 80 extending transversely across the pleats and having their ends secured to the garment, and said elastic strips being secured to the pleated strip at spaced intervals between the plaits.

In testimony whereof I affix my signature.

FRANK E. MCGILL.
